UNITED STATES PATENT OFFICE

MARTHA OTIS CABELL, OF SAN DIEGO, CALIFORNIA

DESIGN FOR A DOLL

Application filed October 8, 1932. Serial No. 45,262. Term of patent 3½ years.

To all whom it may concern:

Be it known that I, MARTHA OTIS CABELL, a citizen of the United States of America, residing at San Diego, in the county of San Diego and State of California, have invented a certain new, original, and ornamental Design for a Doll, of which the following is a specification, reference being had to the accompanying drawing, forming part thereof.

Figure 1 is a front elevational view of a doll showing my new design, and Fig. 2 is a side elevational view thereof.

I claim:

The ornamental design for a doll substantially as shown.

In testimony whereof, I have hereunto set my hand at San Diego, California, this 1st day of October, 1932.

MARTHA OTIS CABELL.
